UNITED STATES PATENT OFFICE.

ALDEN J. BUSH, OF COLUMBUS, OHIO.

CLOSURE CHECK.

Application filed April 4, 1924. Serial No. 704,276.

To all whom it may concern:

Be it known that I, ALDEN J. BUSH, a citizen of the United States, residing at Columbus, in the county of Franklin and State of Ohio, have invented certain new and useful Improvements in Closure Checks, of which the following is a specification.

This invention relates to improvements in closure checks for doors and the like, it more particularly relating to a device of this kind which has pneumatic checking means and an automatic brake controlled by the air compression.

An object of my invention is to provide a closure check which will be simple in construction, economical in manufacture and effective in operation.

A further object of my invention is to provide an automatic friction brake in a device of the character referred to which will operate to prevent rebound of the closure under the action of an unusual extraneous force.

In the accompanying drawing:

Fig. 1 is an elevation of a device embodying my improvement shown and applied to a closure in this case a door and door case.

Fig. 2 is a longitudinal section with a closing spring omitted.

Fig. 3 is a section on the line 3—3 of Fig. 2.

Fig. 4 is a section on the line 4—4 of Fig. 2.

Fig. 5 is an end view of the brake members.

Fig. 6 is a longitudinal sectional view of a portion of the device showing the brake members in braking position.

Fig. 7 is a vertical section of the spring closing devices.

Referring to the drawings, 1 represents a cylinder the ends of which have threaded thereon caps 2 and 3. The cap 2 is formed with an integral yoke 4 perforated to receive a shaft 5 one end of which has connected thereto a notched disk 6, the other end of which has a threaded bore to receive a screw 7 (see Fig. 7) which confines the washer 8 to retain the shaft in position. A collar 9 is mounted on the shaft to rotate therewith, the shaft and collar being provided with coinciding flat faces for this purpose and a coil spring 9' is placed about the shaft between the arms of the yokes, one end of the spring being connected to the collar and the other end of the spring having a bearing against

the yoke. That end of the shaft which carries the notched disk, in the present case the lower end, is secured by a screw 10 to an arm 11 of a bracket 12 which bracket is fastened to the door case 13. The arm of the bracket carries a pawl 6' to engage with the notched disk, as a result of which when the door D is opened the yoke will be rocked about the shaft which is confined against movement by the engagement of the pawl with the notched disk which places the spring under tension to close the door or other closure. The adjustment of the spring may be effected by causing the pawl to engage in any one of the notches of the disk.

Slidably mounted in the cylinder is a piston 14 which has a short stem 15 which has integrally formed therewith a wedge member 16 having a pair of oppositely-arranged incline faces 17 of the wedge, and which has fixed thereto a projecting sleeve 18 which is slidably mounted upon the inner end of a piston rod 19, the forward end of the rod being pivoted to a bracket d on the door D. The sleeve has a slotted opening 20 into which projects a pin 21 carried by the rod so that the sleeve and rod may have a limited movement relatively to each other. A coil spring 22 interposed between the cam member and a block 24 secured to the rod 19 by the pin 25 serves to hold the piston and its connected parts to the rod 19 in distended relation. The piston is of that kind which has an annular recess and carries a flexible sleeve cup 26 which is confined between washers 27 and 28 and which permits air to pass by the piston when the door is opened but is air tight when the door closes, the washers and cup being clamped between the piston and the inner end of the cam member when the piston is screwed upon the stem. The disk 29 is confined between an extension 30 of the block 25 and a cotter pin 31 to act as a guide. The cylinder has a plurality of small apertures 32 placed at different points in the length thereof to permit the escape of the air during the closing movement of the parts and the resistance of the spring 22 is such that under normal conditions the parts will be maintained in the position shown in Fig. 2. In the event, however, that unusual pressure should be brought upon the door or other closure by slamming or wind gusts to thereby increase the pressure of air in the cylinder the piston and the member connected therewith will be

temporarily arrested against the tension of the spring 22 which actions brings into operation braking devices now to be described.

Loosely mounted upon the ends of the pin 5 are wear plates 33 the ends of the pin extending through apertures 34 in these plates. The forward ends of the plates rest on the lower ends of the inclined faces 17. When the movement is imparted between the piston 10 and the rod 19, this results in causing the inclined faces 17 to expand the plates 33 to the position shown in Fig. 6. Each of the plates has a laterally projecting pin 35 and mounted upon these pins 35 are semi-cylindrical brake shoes 36; each brake shoe being provided with an aperture 37 to loosely receive the corresponding pin 35, and also having a boss 36' about the aperture therein which rests upon the corresponding plate 20 which acts to maintain the shoe in parallel relation with the cylinder wall. Each of these brake shoes is preferably faced with leather 38 and the ends of the shoes are resiliently connected together by springs 39, 25 each spring being a piece of spring wire of semi-cylindrical form having its ends bent and inserted in small apertures in the ends of the respective brake shoes. The combined diameters of the two brake shoes and their 30 coverings are somewhat less than the inner diameter of the cylinder so that the brake shoes are out of contact with the interior of the cylinder being so held by the springs 39. In the event, however, of an undue pressure 35 upon the door or other device which it is closing resulting in an increased pressure of air in the cylinder, the piston will be temporarily arrested which will cause the wear plates to ride upon the inclined faces 17 and thereby wedge the brake shoe members into frictional engagement with the interior of the cylinder as clearly shown in Fig. 6. This 40 temporarily locks the door against both closing and rebound which effect continues until the normal air pressure tension has been restored in the cylinder, whereupon the spring 22 will throw the piston to distended position, relatively to the rod 19 causing the wedge to be withdrawn from engaging position, thereby releasing wear plates 33 from 45 engagement from the inclines 17. This engaging and releasing action is in direct correspondence with and in direct proportion to the amount of compression ahead of the piston. Consequently it automatically acts 50 to take care of any unusual force tending to affect the closing movement of the door.

Having thus described my invention, I claim:

60 1. In a device of the character described, the combination, of a door spring with a cylinder connected therewith and a piston; a supplemental device normally out of engagement with the cylinder, and means for automatically connecting the cylinder with the

supplemental device whenever any abnormal force tends to cause a rebound of the door.

2. In a device of the character described, the combination, of a door spring with a cylinder connected therewith, an air operated piston, a supplemental device moving simultaneously with said piston, means for intermittently operating said device to engage the cylinder whenever the door tends to rebound by an abnormal force and for releasing said engagement as soon as said force has spent itself.

3. In a device of the character described, a cylinder, a piston in said cylinder, a piston rod connected with said piston in a manner to permit said piston to have a limited movement relatively to the rod, supplemental devices movable with said rod to co-operate with the inner wall of said cylinder, and means operated by the piston when moved relatively to the rod for operating said supplemental devices.

4. In a device of the character described, a cylinder, a piston in said cylinder, a piston rod, means including a spring for connecting the piston and rod in a manner to permit the piston to have a limited movement relatively to the rod against tension of said spring, supplemental devices movable with said rod to co-operate with the interior of the cylinder, and means movable with said piston for throwing said supplemental devices into engaging position, when said piston moves relatively to the rod.

5. In a device of the character described, 100 a cylinder, a piston in said cylinder, a piston rod connected with said piston in a manner to permit a limited movement of said piston in the direction of said rod but independently thereof, a spring for normally holding said piston against such movement, said piston co-operating with the fluid in said cylinder to regulate the movement of said rod through said cylinder, supplemental devices movable with said rod, and a cam carried by said piston to throw said supplemental devices to engaging position against the walls of said cylinder when said piston is given a movement relatively to said rod by an increased pressure of fluid in said cylinder.

6. In a device of the character described, a cylinder, a piston in said cylinder, a piston rod, a connection between said piston and rod such as to permit the piston to move relatively to said rod, a spring to resist such movement, a pair of semi-cylindrical shoes loosely carried by said rod, and a pair of cams carried by said piston to co-operate with said shoes to force the same against the interior walls of said cylinder when said piston moves relatively to said rod.

7. In a device of the character described, 125 a cylinder, a piston in said cylinder, a piston rod connected with said piston in a way

to permit said piston to move a limited distance relatively thereto, a spring to resist such movement, said piston cooperating with the fluid in said cylinder to check the movement of said rod, said cylinder having apertures for permitting the escape of the air, a pair of wear plates loosely carried by

said rod, a pair of shoes loosely carried by said wear plates, and cams carried by said piston cooperating with said plates. 10

In testimony whereof, I have hereunto set my hand this 25th day of March 1924.

ALDEN J. BUSH.
